UNITED STATES PATENT OFFICE.

GERALD W. HART, OF WEST HARTFORD, CONNECTICUT, ASSIGNOR TO THE HART & HEGEMAN MANUFACTURING COMPANY, OF HARTFORD, CONNECTICUT.

DESIGN FOR AN ELECTRIC-SWITCH BASE.

SPECIFICATION forming part of Design No. 26,650, dated February 16, 1897.

Application filed September 28, 1896. Serial No. 607,266. Term of patent 14 years.

To all whom it may concern.

Be it known that I, GERALD W. HART, a citizen of the United States, residing at West Hartford, county of Hartford, and State of Connecticut, have invented and produced a new and original Design for Electric-Switch Bases, of which the following is a specification, reference being had to the accompanying drawing.

- o The drawing is a perspective view of a switch-base embodying my design.
- 5 The leading or principal feature in my design is a configuration of substantially cup-like shape having vertical grooves extending from the top to the bottom of the walls of the cup, open throughout their lengths and also open at top and bottom, the grooves being so related that in a proper side elevation more than one will be plainly visible.

o A is the wall of the cup-like base.

B is the bottom.

C is the central space within the cup-like base, and D D are the grooves extending from one end to the other of the wall A. These

grooves extend from the top to the bottom, so 25 as to be open at both ends as well as throughout their lengths. Such a base thus presents to the eye a substantially circular cup-like body and also a cup-like body having grooves extending from top to bottom of the wall of 30 the cup, each open at both ends and throughout its length, more than one of which are visible in the proper side view.

As shown, there are in addition small open channels d d, leading from the vertical grooves 35 to the interior of the cup, which are usually used in connection with my design. The interior space is of any form that will accommodate the particular switch mechanism that may be used therein.

What I claim is—

The design for a switch-base, substantially as described and shown.

GERALD W. HART.
